ABSTRACT: A calculating machine having a 10-digit keyboard is provided with a register for temporarily storing values and is selectively engageable with the actuating mechanism to receive values therefrom. A function lever is operatively connected to the register through a linkage which laterally displaces the register in response to positioning of the function lever to cancel decimal positions. The frame of the register is also provided with a lever which is engageable with the actuating mechanism for rounding off the decimal value before the cancelled positions.

CALCULATING MACHINE WITH A DEVICE FOR ROUNDING OFF AN AMOUNT AND FOR CANCELLING DECIMAL POSITIONS

The present invention relates to a calculating machine having a 10-digit keyboard, more particularly, to such a calculating machine having a device to round off the amount behind a decimal point and to cancel decimal positions after the rounded off amount.

Various kinds of calculating machines have been provided with the devices for upward and downward rounding off values. Such rounding off devices have been used together with laterally displaceable counter and storage units and with decade switching. These calculating machines have generally been equipped with the so-called Sundstrand decade switching wherein an additional decimal position can be added only after an increase in time in the transfer of such decades and this increase in time occurs at the expense of increasing the time of other switching operations in the machine. Such an arrangement introduces extremely high degrees of sensitivity of switching functions which is a known characteristic of such prior art calculating machines. The state of the art of such devices was such that a blind transfer unit was required beside the lowest decimal position. This, in turn, necessitated the use of additional switching elements with respect to the individual decimal positions which were to be cancelled. It was readily apparent that such an arrangement was unsatisfactory.

It is therefore the principal object of the present invention to provide a novel and improved device for cancelling decimal positions simultaneously with rounding off amounts in a calculating machine.

It is another object of the present invention to provide a calculating machine having a device which cancels automatically decimal positions while simultaneously upwardly or downwardly rounding off values.

The objects of the present invention are obtained in a calculating machine having a 10-digit keyboard and including an actuating mechanism for transferring values wherein this mechanism comprises a number of differential rack members. A register for temporarily storing values is mounted for lateral displacement within the calculator. The register is supported by cam lever means so as to have limited vertical movement into and out of engagement with the actuating mechanism so that values can be stored from the actuating mechanism into the register. A pivotally mounted function lever is operatively connected to the register through a linkage system to laterally displace the register to cancel a selected number of decimal positions. A lever may be pivotally mounted on the register frame and is operatively engageable with the actuating mechanism to round off the last decimal value before the cancelled decimal position prior to transferring the value to a counter.

The laterally displaceable temporary storage register thus functions simultaneously as a device for cancelling decimal positions and for upwardly and downwardly rounding off values. A decimal point lever is also provided to move the decimal-point-type member to position the decimal point with respect to the cancelled decimal position.

Other objects and advantages of the present invention will be apparent upon reference to the accompanying description when taken in conjunction with the following drawings, which are exemplary, wherein:

FIG. 1 is a longitudinal view through a calculating machine incorporating the present invention and showing only those components of the machine which comprise the invention and are necessary for comprehension of the invention;

FIG. 2 is a perspective view in enlarged scale of the laterally displaceable temporary storage register and the operating mechanism therefor with these components and the rounding off lever being shown in their normal positions;

FIG. 2a is a partial perspective view in enlarged scale of FIG. 2 showing in detail the gears and zero bar;

FIG. 3 is a top plan view of the calculator illustrated in FIG. 1 showing the temporary storage register and decimal-point-shifting mechanism in their normal positions; and

FIGS. 4-7 are partial top plan views showing the actuating mechanism for the temporary storage register in four different switching positions.

Proceeding next to the drawings wherein like reference symbols indicate the same parts throughout the various views a specific embodiment of the present invention will be described in detail.

The calculating machine shown in FIG. 1 which incorporates the present invention is an adding and subtracting machine having a printing unit. The machine includes a 10-button keyboard 1, a laterally displaceable setpin carriage 2, and a plurality of reciprocating spring-loaded actuating members of the differential rack type. There is also provided a laterally fixed counter 4, a storage unit 5 and a temporary storage register 6 which may also be described as a memory unit. These components of the machine as well as the memory unit 6 are driven through a cam and linkage system comprising members 7-15 from a main actuating shaft as known for this type of calculator. It is therefore not necessary to describe these functional components in further detail for comprehension of the invention.

The particular structural unit of the above described calculating machine which incorporates the present invention is the temporary storage register 6 which comprises a frame 18 pivotally mounted on a shaft 17 fixed between sidewalls 16 of the calculating machine. The register 6 is illustrated in greater detail in FIGS. 2, 2a and 3 and the sidewalls of the machine are shown in FIG. 3.

Another shaft 19 is rotatably supported within the calculating machine and has a pair of control levers 20 fixed at its end with the upper portions of these levers being provided with curved cam slots 21 which support a shaft 22. The shaft 22 has a plurality of gears 23 thereon with each gear being provided with a lateral zero cam 24 (FIG. 2a) facing a zero stop bar 25 on register frame 18 and having a number of abutment stop dogs 26. The gears 23 can be coupled temporarily to transfer members 43 of the actuating mechanism 3 and/or decade levers 34 in order to introduce a value into the gears of the register 6. As the control levers 20 are pivoted by means of link 15 which is pivotally connected to one of the levers, the cam slots 21 will move shaft 22 together with gears 23 upwardly so that the gears are temporarily coupled with the transfer members 43. The value introduced into the register 6 by means of the gears 23 is temporarily retained therein and then withdrawn.

The register 6 is also slidably moveable upon the shaft 17 so as to be laterally displaceable within the calculator. For this purpose, the shaft 22 is provided with a cam follower 28 which, together with other elements which are to be presently described, displace the register for the purpose of cancelling decimal positions.

For the upward and downward rounding off operation a trip lever 29 is pivotally mounted on the shaft 19 and is retained by a tension spring 30 against a pin 32 on a rocking lever 32 on an end of a known type of locking shaft 33 for blocking a decade lever 34. Another switching lever 35 is mounted on the shaft 19 together with a torsion spring 36 also mounted on the shaft 19 with the spring retaining the switching lever 35 and the trip lever 29 in their operating positions.

The trip lever 29 is provided with a pin 37 which rests on the switching lever 35 and arrests the upward pivotal movement of this lever. The lever 35 is provided with a nose projection 38 which is engageable in an upward direction against a feeler lever 39 to temporarily lift this feeler lever and pivot the same in a clockwise direction. The locking shaft 33 is pivoted in a known manner in a counterclockwise direction for locking decade levers 34 for total and subtotal operations.

The trip lever 29 is provided with a cam projection 40 acted upon by the pin 31 so that the trip lever 29 is pivoted together with the pivoting of the feeler lever 39. A spring 39' urges feeler lever 39 in a counterclockwise direction so that a tab 41

is positioned as shown in FIG. 1. The upward pivoting of feeler lever 39 causes tab 41 to engage teeth 42 of a particular transfer member 43. This sensing function is performed during the initial phase of the machine operation so that the lever 39 will not actuate a decade lever 34. The torsion spring 36 prevents any blocking of these operational components.

The lateral displacement of the temporary storage register 6 with the simultaneous actuation of the feeler lever 39 can be selected by the operator. The displacement is achieved by the cam follower 28 which receives a pin 46 riveted to an arresting lever 45 pivotally mounted on a bearing pin 48 firmly attached to a base plate 47. A tension spring 49 urges the arresting lever 45 in the direction indicated by the arrow in FIG. 2.

A downwardly extending pin 50 is riveted to a rear portion of the arresting lever 45 and is retained in operative relationship with a stop slide having steps 52 and 100. The pin 50 is being shown in engagement with step 52 in FIG. 2. The stop slide 51 is mounted for longitudinal sliding movement and has at its other end an upstanding lug 53 connected by means of a pin 54 to a functional or rounding off lever 55. The lever 55 is pivotally mounted on a bearing shaft 56 extending from a sidewall 16 of the calculator as may be seen in FIG. 3. A pin 57 also mounted in the sidewall 16 pivotally supports a catch lever 58 which is urged downwardly in the direction of the arrow indicated at a tension spring 59. The lower edge of the lever 58 is provided with a plurality of notches 60, 61 and 62 which receive a catch pin 63 mounted on the rounding off lever 55 with these notches determining operating positions of the lever.

A second stop slide 64 is supported for longitudinal displacement on the base plate 47 by means of a stationary pin 65 received within a longitudinal slot 66. A tension spring 68 is connected to an angular arm 67 extending from slide 64 and urges the slide in the direction indicated by the arrow attached to the spring. A longitudinal surface 69 of slide 64 bears against a roller 70 mounted on a bearing pin 71 upstanding upon the base plate 47.

The angular arm 67 of the slide is engageable with the lower portion 72 of a decimal point lever 73 pivotally mounted on the bearing shaft 56. The upper end of lever 73 is received within a slot formed in a pull member 74. A pin 75 on the lower end of the decimal point lever 73 is engageable with notches 76 and 77 on a pivotally mounted catch lever 79 which is urged downwardly by a spring 78 in the direction of the arrow thereon.

The pull member 74 is guided at its other end by means of a longitudinal slot 84 therein receiving a pin 81 attached to a pivotable switching lever 82. Lever 82 is provided with a pin 83 received in a cam follower 84 mounted on an end of a decimal shaft 85 which is axially moveable in the frame walls 16 of the calculator. The pull member 74 is also provided with a pin 86 which engages a curved slot 87 in the switching lever 82 and a tension spring 88 connected to the pull member 84 urges the member in a direction indicated by the arrow on the spring.

Also mounted on the bearing pin 71 is an upper lever arm 89 having a curved cam surface 90 which is engageable with the pin 50 on the arresting lever 45. Also mounted on the bearing pin 71 is a lower lever arm 91 provided with a pin 92 which is connected to a rod 93 guided for movement in the direction of the arrow on the rod. The rod 93 is pivotally connected by a rivet connection 94 to a lever 95 which is driven automatically by the main actuating shaft of the calculating machine such as during a subtotal operation of the machine.

The function lever 55 initiates the operation of cancelling decimal positions in the same manner as the decimal point lever 73 sets the decimal point. The function lever 55 has three operating positions as follows:

A first or frontal position where pin 63 is retained in notch 60 as shown in FIGS. 3 and 4 and the cancelling operation does not occur.

A second or central position where the pin 63 is engaged in notch 61 and two decimal positions are cancelled. This position is illustrated in FIG. 5.

5 A third or rear position wherein the function lever pin 63 is engaged in notch 62 and four positions are cancelled. This position is shown in FIG. 7. When function lever 55 is in its normal forward position, as shown in FIGS. 2 and 4, the maximum step 52 of stop slide 51 engages pin 50 on arresting lever 45 whose pin 46 positions cam follower 28 and the temporary storage register 6 in its normal right-hand position. In this position, all of the gears 23 are correspondingly positioned with respect to all of the transfer members 43 and may mesh with the teeth of the transfer members 43. The feeler lever 39 faces a shorter decade lever 34 which cannot be engaged by the lug 44.

10 When the function lever 55 is shifted into its second or central position, the stop slide 55 is shifted to the left as may be seen in FIG. 5 such that the arresting lever pin 50 is no longer engageable with the step 52 but rests upon a step 96 on the second stop slide 64. The spring 49 pivots arresting lever 45 to the position as shown in FIG. 5 so that the pin 46 moves the cam follower 28 and shaft 22 into a position wherein the register 6 is moved to the left through two decimal positions.

15 The decimal-point-type member 97 mounted on the decimal point shaft 85 is normally set and positioned between the second and third decade positions as shown in FIG. 3. If the decimal point lever 73 is now actuated, the pull rod 74 will be shifted to the left whereupon the pin 86 in the slot 87 will shift lever 82 in a counterclockwise direction so that pin 83 engaged in the cam follower 84 will move shaft 85 toward the left by one decimal position. In this position, the decimal-point-type member 97 will be shifted to the next higher decimal position.

20 At the same time that the decimal point lever 73 was actuated, the stop slide 64 was also shifted to the left because of its engagement with the lower arm 72 of the decimal point lever. As a result, the arresting lever pin 50 engages abutment step 98 to shift the register 6 to the left an additional decimal position so that at this point three decimal positions have been cancelled.

25 After the decimal point lever 73 has been shifted back into its normal position, the decimal-point-type member 97 will also be moved back into its normal position opposite the second decade member. During this return movement, the stop slide 64 cannot move under the action of its spring 68 since the pin engages an abutment step 99 to prevent this return movement. The pin 50 will release the stop slide 64 only after the register 6 has been returned to the right to its normal starting position. When this occurs, the slide 64 can then also return under the influence of its tension spring 68 as may be seen in FIG. 6.

30 When the function lever 55 is switched to its third or rear position so that its pin 63 is engaged in the notch 62, the stop slide 51 is further shifted to the left so that the arresting lever pin 50 is now positioned in front of abutment step 100. The slide 51 is further provided with a rear abutment 101 which is positioned in front of a pin 102 on stop slide 64 to prevent the stop slide from being positioned within the range of arresting lever pin 50. The pin 50 now rests on abutment step 100 of slide lever 51 so that the arresting lever 45 can now shift the register 6 four decimal positions to the left so that four decimal positions are cancelled. This position of the slides is shown in FIG. 7.

35 After the third switching function has been completed, the register 6 is automatically returned to its normal position. This is accomplished through the main drive of the calculator 65 wherein the member 95 pulls the rod 93 which in turn pivots the lower lever arm 91 and pin 71 to cause the cam surface 90 on upper lever arm 89 to engage the rear face of the arresting lever and pivot this lever toward the right to return register 6 to its normal position.

40 The downward and upward rounding off operation is simultaneously carried out by the feeler lever 39 during an additional subtotal operation of the calculating machine.

45 The feeler lever 39 is normally positioned so that it is displaced to the right by one decimal position from the first gear 75 of the gears 23 of the register 6. If the register 6 is then shifted

to the left by two decimal positions, the first of its gears 23 faces the third transfer member 43 of counter unit 4. The lug 44 of feeler lever 39 will then be positioned in front of a decade lever 34 for the third decimal position while the lug 41 faces a transfer member of the second decimal position. As a result, there are no gears 23 associated with the transfer members 43 of the first and second decade positions.

In this subtotal operation of the calculating machines, the transfer member 43 sense the value in the counter unit 4 in a known manner. The trip lever 29 will then urge the feeler lever 39 upwardly against the correspondingly positioned transfer member 43. If the transfer member 43 was not shifted by more than five units in sensing the value from counter 4, the lug 41 will be positioned on a point of a tooth 42 on the transfer member 43. However, if the transfer member 43 was moved more than five units, the lug 41 will be positioned between the teeth of transfer member 43 in the dotted line position 41' as shown in FIG. 2. In this situation, the feeler lever 39 will be pivoted to such an extent that its bent lug 44 will release a decade lever 34. When the transfer members 43 are restored, a decade transfer to the third transfer decade position of the counter unit 4 will be carried out and the upward rounding off operation will be completed.

Thus it can be seen that the present invention has disclosed a calculating machine wherein the rounding off operation occurs simultaneously with the cancelling of excessive decimal positions. These results are achieved by the lateral displacement of a temporary storage register whose frame is further provided with a feeler lever functioning during the rounding off operation. The entire arrangement is simple and compact and operates satisfactorily with a minimum of difficulty.

It is understood that this invention is susceptible to modification in order to adapt it to different usages and conditions and, accordingly, it is desired to comprehend such modifications within the invention as may fall within the scope of the appended claims.

What I claim is:

1. In a calculator having a 10-digit keyboard, the combination of an actuating mechanism for transferring values, a register for temporarily storing values and mounted for lateral displacement, cam lever means supporting said register for limited vertical movement into and out of engagement with said actuating mechanism, function lever means operatively connected to said register for laterally displacing the register to cancel a selected number of decimal positions, and means mounted on said register and operatively engageable with said actuating mechanism for rounding off the last decimal value before the cancelled decimal positions prior to transferring the value to a counter.

2. In a calculator as claimed in claim 1 wherein said register comprises a shaft and a plurality of value-receiving gears thereon, said cam lever means comprising a pair of spaced levers having curved slots therein supporting said register shaft.

3. In a calculator as claimed in claim 2 and comprising a lateral zero cam for each gear, and a zero stop bar on said register and having stop abutment dogs operatively engageable by said zero cams.

4. In a calculator as claimed in claim 1 wherein said calculator has a counter and a decade lever for each decimal position, said register comprising a frame, said rounding off means

comprising a lever pivotally mounted on one side of said register frame, a first tab on one end of said lever and a second tab on the other end thereof, said first tab being temporarily engageable with said actuating mechanism while the second tab simultaneously releases a decade lever so that a value may be transferred to the counter upon restoring of the actuating mechanism.

5. In a calculator as claimed in claim 4 and comprising a second shaft having a trip lever with a cam projection and a switch lever with a nose projection pivotally mounted thereon, torsion spring means on said second shaft and acting against said trip and switch levers, a blocking shaft lockingly engageable with the decade levers and having a rocking lever thereon with a pin, spring means urging the cam projection of said trip lever against said rocking lever pin, said switch lever nose projection being retained in position against said rounding off lever.
6. In a calculator as claimed in claim 1 and comprising means for retaining said function lever in a selected one of three operating positions, a first stop slide having two abutment steps operatively connected to said function lever and slideable longitudinally within the calculator, an arresting lever having a pin engageable with the abutment steps of said first stop slide, and means operatively connecting said arresting lever and said register for laterally displacing the register in response to actuation of said function lever together with the first stop slide and arresting lever.
7. In a calculator as claimed in claim 1 and comprising a pivotally mounted decimal point lever, means for retaining said decimal point lever in a selected one of two operating positions, and a second stop slide having one end operatively connected to said decimal point lever and slideable longitudinally within the calculator.
8. In a calculator as claimed in claim 6 and comprising a pivotally mounted decimal point lever, means for retaining said decimal point lever in a selected one of two operating positions, a second stop slide having one end operatively connected to said decimal point lever and slideable longitudinally within the calculator, said second stop slide having two steps at the other end thereof engageable with the pin on said arresting lever, and means responsive to actuation of said decimal point lever for positioning a decimal point printer unit with respect to the cancelled decimal positions.
9. In a calculator as claimed in claim 7 and comprising roller means engaging a longitudinal edge of said second stop slide, and means engageable with said second stop slide for supporting the same in the longitudinal direction of displacement.
10. In a calculator as claimed in claim 6 and comprising a double lever having upper and lower arms pivotally mounted for movement about the same axis, operating linkage pivotally connected to said lower lever arm, said upper arm having a cam surface engageable with the pin on said arresting lever, said cam surface acting against said arresting lever pin in response to the operating linkage actuating said double lever to return the register to its normal position.
11. In a calculator as claimed in claim 1 and comprising an axially moveable shaft having a decimal-point-type member thereon, and linkage means operatively connected to said type member shaft and responsive to the lateral displacement of said register through two decimal positions for moving said decimal-point-type member one decimal position.
